UNITED STATES PATENT OFFICE.

GEORGE WILKINSON, OF PROVIDENCE, RHODE ISLAND, ASSIGNOR TO THE
GORHAM MANUFACTURING COMPANY, OF SAME PLACE.

DESIGN FOR A SPOON.

SPECIFICATION forming part of Design No. 21,045, dated September 15, 1891.

Application filed July 2, 1891. Serial No. 398,317. Term of patent 7 years.

To all whom it may concern:

Be it known that I, GEORGE WILKINSON, a citizen of the United States, residing at Providence, in the county of Providence and State of Rhode Island, have invented and produced 5 a new and original Design for the Ornamentation of the Handles of Spoons, Forks, &c.; and I do hereby declare the following specification, taken in connection with the accompanying drawings, forming a part of the same, 10 to be a description thereof.

In the illustrations, Figure 1 represents a front or face view of a spoon the handle of which is ornamented with the design. Fig. 15 2 shows a rear view of the spoon with the design upon that face of the handle.

Upon the faces of the spoon-handle and following the outline thereof the design is arranged and composed as follows: At the head 20 of the handle A, upon its front face, is located a shell-like ornament 1. Below this, on the left-hand side, is a compound leaf-scroll 2. Below this scroll are located in succession three leaf-scrolls 3 4 5, the last mentioned extending to the lower end of the handle. On 25 the right-hand side of this face and below the ornament 1 is located a beaded scroll 6, and immediately thereunder a compound leaf-scroll 7 7 7. Below this compound scroll is arranged a beaded scroll 8, and immediately 30 thereunder a scroll 9, which extends to the lower end of the handle. On the rear face of the handle a shell-like ornament 10 is located at the head of the handle, and below this, on the left-hand side, is arranged a beaded scroll 11. Below this is a compound scroll 12 12, 35 and below this in succession are scrolls 13 14, the latter extending to the lower end of the

handle. On the right-hand side and below the ornament 10 are two leaf-scrolls 15 16, and 40 below these scrolls a compound scroll 17 is arranged, below which is a scroll 18, which extends to the lower end of the handle.

What I claim, and desire to secure by Letters Patent, is—

1. In a design for the ornamentation of the handles of spoons, forks, &c., the shell-like ornament 1, located at the upper end of the handle, and the scrolls 2 3 4 5 6 7 8 9, extending upon the face downwardly from said ornament along the outline of the handle, substantially as described and shown.

2. In a design for the ornamentation of the handles of spoons, forks, &c., the shell-like ornament 10, located at the upper end of the handle, and the scrolls 11 12 13 14 15 16 17 18, 50 extending downwardly from said ornament along the outline of the handle, substantially as described and shown.

3. In a design for the ornamentation of the handles of spoons, forks, &c., the shell-like ornament 1, located at the upper end of the handle upon one of its faces, and the scrolls 2 3 4 5 6 7 8 9, extending upon said face downwardly from said ornament along the outline 65 of the handle, the shell-like ornament 10, located at the upper end of the handle on its opposite face, and the scrolls 11 12 13 14 15 16 17 18, extending upon this face downwardly from the ornament 10 along the outline of the 70 handle, substantially as described and shown.

GEORGE WILKINSON.
